TYPOGRAPHICAL COMPOSING MACHINE

James G. McNamara, Brooklyn, N. Y., assignor
to Mergenthaler Linotype Company, a corpora-
tion of New York

Original application June 24, 1933, Serial No.
677,417. Divided and this application March
17, 1934, Serial No. 716,181. In Great Britain
and Germany October 21, 1933

15 Claims. (Cl. 199—46)

This invention relates to typographical machines, such as those of the general organization represented in Letters Patent of the United States No. 436,532 to O. Mergenthaler, wherein circulating matrices are released from a magazine in the order in which their characters are to appear in print and then assembled in line, the composed line transferred to the face of the mold, the mold filled with molten metal to form a slug against the matrices which produce the type characters thereon and the matrices thereafter elevated and returned through distributing mechanism to the magazine from which they started. More particularly, it relates to machines wherein the magazine is pivotally mounted in the machine frame and is movable from a position parallel with the magazine supporting frame, wherein it cooperates with the matrix releasing escapements which remain in the machine at all times, to a position clear of the escapements, to facilitate the removal of the magazine and its replacement by a magazine containing a different matrix font.

The present invention is directed to certain improvements in machines of the class stated, and intended to simplify the construction and facilitate the locking of the matrices in the magazine prior to the removal thereof from the machine. To this end, the magazine containing the different fonts with which the machine is adapted to be equipped are provided each with a matrix locking bar which is automatically shifted to active position as the magazine is separated from the escapement mechanism to facilitate its removal, and the locking bar of the substitute magazine automatically shifted to inactive position as such magazine is brought into engagement with the escapement mechanism to permit the operation thereof in the usual manner to release the matrices.

In another of its aspects, the invention comprehends an arrangement whereby the matrices in the magazine on the machine may be transferred to a storage magazine and other matrices transferred from a second storage magazine to the main magazine without removing the latter from the machine.

This application is a division of my copending application Serial No. 677,417 filed June 24, 1933.

Referring to the drawings:

Fig. 1 is a side elevation of a portion of a linotype machine showing a magazine in a partially raised position, the means for raising and lowering the magazine and the means for automatically operating the matrix lock;

Fig. 2 is a side elevation similar to Fig. 1, with the parts in normal position;

Fig. 3 is a side elevation similar to Fig. 1, showing the parts in a position just prior to raising the magazine from the frame;

5

Figs. 4 and 5 are partial front elevations of the parts shown in Figs. 1 to 3;

Figs. 6 and 7 are partial sectional views on lines 6—6 and 7—7 of Figs. 2 and 1, respectively;

Fig. 8 is a side elevation of a portion of the machine, showing the devices for transferring matrices from and to the main magazine without removing the latter from the machine;

10

Fig. 9 is a partial front view of the parts shown in Fig. 8; and

15

Fig. 10 is a section, partially broken away, on line 10—10 of Fig. 8.

The matrices are stored in a channeled magazine A resting on a base frame A¹ and pivotally mounted in the machine to permit movement into and out of operative position with the usual assembler entrance or raceway (not shown but positioned as usual at the lower end of the magazine). The magazine in its operative position cooperates with a bank of escapements A² fixed to the base frame and operated in the usual way from a keyboard mechanism to release the matrices one at a time for stacking in the assembler (not shown) to form a composed line. Thereafter the line is transferred to the first elevator or transporter which descends to present the composed line to the mold, the mold advanced into close contact with the matrix line, the mold filled with molten metal to form a slug against the matrices which produce the type characters thereon, and the matrices thereafter elevated and returned through a distributing mechanism positioned at the upper end of the magazine A to the respective channels of the magazine from which they started.

20

In order that different fonts may be used with the machine, the magazine A, as previously stated, is pivotally mounted in the machine so that it may be raised from its normal position, parallel to the magazine supporting frame A¹ to effect its removal and replacement by a magazine containing a different font. When the magazine A is in its normal position, the matrices, of course, are held therein by the escapement pawls which cooperate with the upper projecting ears of the matrices to effect their release one at a time, but when the magazine A is separated from the escapements A², some means must be provided for locking the matrices to prevent them from spilling out of the magazine.

55

As more fully described in my Patent No. 1,586,316, the separation of the magazine A from its supporting frame A¹ is effected by means of a pair of hand levers A⁵, A⁶, one positioned at each end of a transverse rock shaft A⁷ journaled in the magazine frame. When the magazine is in its normal position, the levers A⁵, A⁶ occupy the position shown in Figs. 2 and 4, with hook portions a² engaging at opposite ends of the customary forward transverse rib a³ on the underside of the magazine to hold the latter securely in position. The magazine supporting frame A¹ is provided with a central magazine lifting and supporting plate A⁸ (Fig. 8) pivoted at its upper end to the frame, which thus permits it to be swung upwardly in lifting the magazine; the plate A⁸ at its lower end, being provided with stop shoulders a⁴ normally engaged with the rib a³, and which thus retain the magazine in place on the plate A⁸ when the latter is in its raised position.

In the embodiment illustrated, the swinging of the magazine lifting and supporting plate A⁸ is controlled and effected by a cam a⁵ or equivalent device arranged near the lower end thereof and fast to the transverse rock shaft A⁷ journaled in the base frame A¹. Thus, when the hand levers A⁵, A⁶ are pulled forwardly, the magazine is first released from the magazine frame by the disengagement of the hooks a² with the rib on the magazine, and the magazine raised by the engagement of the cam a⁵ with the magazine supporting plate A⁸, this action resulting in the separation of the magazine from the escapements A².

When the magazine is separated from the escapements, the matrices are prevented from spilling out by a locking bar A⁹ extending transversely of the magazine, and provided with a series of depending teeth a⁶ at its front edge, which are adapted to stand across or in front of the lower ears of the leading matrices in the magazine channels when the locking bar A⁹ is actuated to the right (Figs. 5 and 7), thus preventing their escape from the magazine, but which are adapted to stand clear of said ears when the locking bar is actuated to the left (Figs. 4 and 6) to permit the release of the matrices from the magazine.

The transverse movements of the locking bar are effected automatically by a pair of cams a⁷, a⁸, one mounted on each of the hand levers A⁵, A⁶, the cam a⁷ on the left having a surface a⁹ sloping inwardly toward the side of the magazine and which engages the left end of the locking bar A⁹, actuating it to the right or locking position when the levers are drawn forwardly to raise the magazine, and the cam a⁸ on the right having a surface a¹⁰ sloping away from the magazine, and which is adapted to engage the right end of the locking bar A⁹ to actuate it to unlocking position when the hand levers are pushed rearwardly in returning the magazine to normal position, wherein it engages the escapements. The cam surfaces are complementary in nature, the slope of the cam surface a¹⁰ on the right providing the necessary clearance for the locking bar as it is actuated to the right by the locking cam a⁷, and the slope of the surface a⁹ of the latter cam providing the necessary clearance for said bar when it is actuated to the left under the influence of the unlocking cam a⁸.

As shown in Figs. 6 and 7, the rear faces of the teeth a⁶ are bevelled, so that as they are projected across the magazine channels by the movement

of the locking bar A⁹ to the right, they will push the matrices rearwardly a slight distance, and thus provide clearance between the matrices and the escapements as the magazine is removed from or replaced in the machine. The bevelled surfaces also facilitate the cooperation of the teeth with the matrices.

In order to maintain the bar A⁹ in its locking position when the magazine is removed, the latter is provided at the right with a pivoted locking pawl a¹¹ arranged to enter a notch a¹² in the upper edge of the bar A⁹ when the latter is in its locking position (Figs. 1 and 7). The lower portion of the pawl a¹¹ engages on the top of the escapement frame A² when the magazine is in operative relation with the latter (Fig. 2), thus maintaining the pawl in its inactive position against the push of a spring pressed pin a¹³ banking on the rear edge thereof. Just prior to the disengagement of the magazine from the escapements, the locking bar A⁹ is actuated to locking position, bringing the notch a¹² in registry with the pawl a¹¹ (Fig. 7), so that as the magazine is raised from the escapements and the pawl freed, the latter is pushed forwardly into the notch by the pin a¹³ thereby retaining the bar A⁹ in locking position. When the magazine is again brought into cooperative relation with the escapements, the pawl a¹¹ banks upon the top of the escapement frame A² and thereby is withdrawn from the notch a¹² to release the locking bar.

In Figs. 8 to 10, there is shown an arrangement whereby the matrices in the magazine on the machine may be transferred to a storage magazine and other matrices transferred from another storage magazine to the main magazine without removing the latter from the machine.

The storage magazines A¹⁰, A¹¹ are each provided with channels corresponding with those of the main magazine A, a pair of transverse ribs a¹⁴, a¹⁵ at the bottom of the magazine, projecting beyond the lateral edges thereof, a shorter transverse rib a¹⁶ at the leading edge of the magazine and the usual locking bar A⁹ for preventing the matrices from spilling out. The hand levers A¹² are of a somewhat different shape from those in the embodiment previously described and are so formed that as they are turned to their forward position to raise the magazine above its supporting frame (Fig. 8), a pair of supporting surfaces are presented upon which the auxiliary magazine rests with its channels in alignment with the corresponding channels of the main magazine. Each of the levers is further provided with a retaining lug a¹⁷ at its forward end arranged to engage the lower transverse rib a¹⁴ to maintain the auxiliary magazine in position on the supporting levers.

The machine is also provided with a hinged magazine entrance channel J¹¹ between the distributor mechanism and the entrance end of the magazine A, which may be turned downwardly out of the way of the auxiliary magazine A¹¹ from which the matrices are to be transferred to the main magazine. The auxiliary magazine A¹¹ is held in position to transfer matrices to the magazine A by a pair of lugs a¹⁸, one arranged at each of the upper corners of the magazine supporting frame A¹, and upon which the front edge of the auxiliary magazine rests with the transverse rib a¹⁶ banking against the rear faces of the lugs, and by a pair of brackets A¹³ supported by the distributor frame at the opposite ends thereof. The brackets are each provided at their

rear ends with a spring actuated dog a^{19} arranged to engage beneath the upper transverse rib a^{15} of the auxiliary magazine, and at the ends thereof to maintain the magazine in a position, where-
 10 in its channels aline with the corresponding channels of the main magazine. Thus, in order to place the auxiliary magazine A^{11} in position it is necessary only to rest the front edge thereof on the magazine supporting frame A^1 and push the rear portion of the magazine up until engaged by the spring actuated dogs a^{19} .

In order to transfer the matrices from the main magazine A to the auxiliary storage magazine A^{10} , the matrix lock of the latter is first locked and the matrix lock of the main magazine unlocked, whereupon the matrices will slide out of the channels of the main magazine into the corresponding channels of the auxiliary magazine. The lock of the main magazine is then locked, and that of the upper auxiliary magazine A^{11} unlocked, whereupon the matrices will slide from the channels of the latter into the corresponding channels of the main magazine. The storage magazines are then removed and the main magazine lowered to its normal position by the rearward movement of the levers A^{12} .

The advantage of the auxiliary magazines resides in the fact that they may be made cheaply, thus obviating the necessity for a number of main magazines corresponding to the different fonts desired to be used with the machine. They are particularly desirable in a machine such as that described in my copending application, Serial No. 677,417, wherein the main magazine is much wider than usual, being designed chiefly for use with "head letter" matrices, and consequently more expensive than standard magazines.

In view of the previous description, it is believed the invention will be readily understood without entering into a further description of the operation of the machine.

In the accompanying drawings the invention has been shown merely by way of example and in preferred form, and obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is as follows:

1. In a typographical composing machine, the combination of a matrix magazine, escapement mechanism therefor, means for separating the magazine from the escapement mechanism, a longitudinally shiftable matrix locking bar, means for automatically shifting the bar longitudinally to active position to lock the matrices in the magazine as the latter is separated from the escapement mechanism, and means operating automatically to lock said bar in active position.

2. In a typographical composing machine, the combination of a matrix magazine, escapement mechanism therefor, means for moving the magazine into and out of engagement with the escapement mechanism, a longitudinally shiftable matrix locking bar, means for automatically shifting the bar longitudinally in one direction to active position to lock the matrices in the magazine as the latter is separated from the escapement mechanism, means for automatically shifting the bar longitudinally in the opposite direction to inactive position as the magazine is brought into engagement with the escapement

mechanism, and means operating automatically to lock the bar when shifted to active position and to release the bar to permit its actuation to inactive position.

3. In a typographical composing machine, the combination of a matrix magazine, escapement mechanism therefor, means for separating the magazine from the escapement mechanism, a longitudinally shiftable locking bar for the matrices, and mechanism including a lever pivoted on the magazine frame and provided with a laterally disposed cam surface cooperating with said locking bar and arranged automatically to cam the bar longitudinally to active locking position as the magazine is separated from the escapement mechanism.

4. In a typographical composing machine, the combination of a matrix magazine, escapement mechanism therefor, means for moving the magazine into and out of engagement with the escapement mechanism, a longitudinally shiftable locking bar for the matrices, and a pair of levers pivoted on the magazine frame and each provided with a laterally disposed cam surface, one cooperating with the locking bar longitudinally in one direction and arranged automatically to cam the bar to active position as the magazine is separated from the escapement mechanism, and the other arranged automatically to cam the bar longitudinally in the opposite direction to inactive position as the magazine again engages the escapement mechanism.

5. In a typographical composing machine, the combination of a matrix magazine, escapement mechanism therefor, means for separating the magazine from the escapement mechanism, a longitudinally shiftable matrix locking bar, means for automatically shifting the bar longitudinally to active position to lock the matrices in the magazine as the latter is separated from the escapement mechanism, and means including a spring pressed pawl acting automatically to lock said bar and maintain it in active position while the magazine is separated from the escapements.

6. In a typographical composing machine equipped with composing and distributing mechanisms, the combination of a main magazine arranged between the composing and distributing mechanisms and having a plurality of matrix channels, a frame supporting the magazine, and means on the frame adapted to support an auxiliary magazine with its matrix channels in alinement with corresponding channels in the main magazine whereby the matrices may be transferred from one magazine to the other without removing the magazine from the machine.

7. In a typographical composing machine, the combination of a main magazine having a plurality of matrix channels, a magazine supporting frame, and a pair of levers pivoted to the frame and arranged when moved to forward position to move the magazine out of operative relation with the assembler throat, said levers being adapted when in such forward position to support an auxiliary magazine with its matrix channels in alinement with corresponding channels of the main magazine, whereby the matrices may be transferred from said main magazine to the auxiliary magazine.

8. In a typographical composing machine, the combination of a main magazine adapted to be supported in the machine and having a plurality of matrix channels, means comprising a pair of brackets attached to the machine frame and arranged to support an auxiliary magazine with

- its discharge end in juxtaposition with the entrance end of the main magazine and with its corresponding matrix channels in alinement with those of the magazine, whereby matrices from the auxiliary magazine may be transferred to the main magazine.
9. In a typographical composing machine, the combination of a main magazine adapted to be supported in the machine and having a plurality of matrix channels, means comprising a pair of brackets attached to the machine frame and arranged to support an auxiliary magazine with its discharge end in juxtaposition with the entrance end of the main magazine and with its corresponding matrix channels in alinement with those of the main magazine, whereby the matrices from the auxiliary magazine may be transferred to the main magazine, said brackets being equipped with means automatically to engage and hold said auxiliary magazine in position when brought into operative relation with the main magazine.
10. In a typographical composing machine adapted to be equipped with a plurality of different matrix magazines, the combination of escapement mechanism, means for supporting the matrix magazine in use in operative relation with the escapement mechanism, means for moving the magazine from operative position to a position wherein the magazine may be removed from the machine, a matrix locking bar in the magazine and means for automatically actuating the bar to lock the matrices in the magazine as the latter is separated from the escapement mechanism and for automatically actuating the matrix locking bar of a substitute magazine to unlock position as said magazine is brought into operative relation with the escapement mechanism.
11. In a typographical composing machine adapted to be equipped with a plurality of different matrix magazines, the combination of escapement mechanism, a pivoted frame for supporting the magazine in use in operative relation with the escapement mechanism, a matrix locking bar in said magazine and means for moving the frame to separate the magazine from the escapement mechanism and bring said magazine into a position wherein it can be removed from the machine, said means including a pair of cams, one arranged to actuate the locking bar to active position as the magazine is separated from the escapement mechanism, and the other arranged to actuate the locking bar of a substitute magazine to inactive position as said latter magazine is moved into operative relation with the escapement mechanism.
12. In a typographical composing machine the combination of a main magazine pivotally mounted in the machine and having a plurality of matrix channels, a matrix locking bar in the magazine, means including a pair of brackets pivoted to the magazine frame and adapted when moved to forward position to move the magazine out of operative relation with the assembler entrance and automatically to actuate the locking bar to active position, said brackets being adapted when in such forward position to support an auxiliary magazine with its matrix channels in alinement with corresponding channels of the main magazine, said matrix locking bar being movable to inactive position when the auxiliary magazine is in place whereby the matrices may be transferred from the main magazine to the auxiliary magazine.
13. In a typographical composing machine the combination of a main magazine pivotally mounted in the machine and having a plurality of matrix channels, a matrix locking bar in the magazine, means including a pair of brackets pivoted to the machine frame and adapted when moved to forward position to move the magazine out of operative relation with the assembler entrance and automatically to actuate the locking bar to active position, said brackets when in forward position being arranged to support an auxiliary magazine with its matrix channels in alinement with corresponding matrix channels in the main magazine, said locking bar being movable to inactive position when the auxiliary magazine is in place to permit the transfer of matrices from the main magazine to the auxiliary magazine and movable to active position to retain matrices transferred from a second auxiliary magazine, said locking bar being automatically actuated to inactive position as the main magazine is again brought into operative relation with the assembler entrance when the bracket means are moved rearwardly to normal position.
14. In a typographical composing machine, the combination of a matrix magazine, a base frame upon which the magazine is supported, escapement mechanism also supported in the base frame, means for lifting the magazine from its normal position upon the base frame to separate it from the escapement mechanism and position it for removal, a matrix locking bar carried by the magazine, and means for automatically actuating said bar to lock the matrices in the magazine as the latter is lifted out of engagement with the escapement mechanism for removal.
15. In a typographical composing machine, the combination of a matrix magazine, a base frame upon which the magazine is supported, escapement mechanism also supported in the base frame, means for lifting the magazine from its normal position upon the base frame to separate it from the escapement mechanism and position it for removal, a matrix locking bar carried by the magazine, means for automatically actuating said bar to lock the matrices in the magazine as the latter is lifted out of engagement with the escapement mechanism for removal, and means for automatically actuating said bar to unlock the matrices in the magazine as the latter is lowered into engagement with the escapement mechanism.

JAMES G. McNAMARA.

CERTIFICATE OF CORRECTION.

Patent No. 2,011,524.

August 13, 1935.

JAMES G. McNAMARA.

It is hereby certified that error appears in the printed specification of the above numbered patent requiring correction as follows: Page 3, second column, lines 25-26, claim 4, strike out the words "longitudinally in one direction" and insert the same after "bar" in line 27, of said claim; and that the said Letters Patent should be read with this correction therein that the same may conform to the record of the case in the Patent Office.

Signed and sealed this 8th day of October, A. D. 1935.

(Seal)

Leslie Frazer
Acting Commissioner of Patents.
